UNITED STATES PATENT OFFICE.

MARK COX, OF DES MOINES, IOWA.

AUTOMOBILE-LIGHT AND DIMMER.

1,293,719.

Specification of Letters Patent. Patented Feb. 11, 1919.

Application filed July 31, 1918. Serial No. 247,684.

To all whom it may concern:

Be it known that I, MARK Cox, a citizen of the United States, and a resident of Des Moines, in the county of Polk and State of

5 Iowa, have invented a certain new and useful Automobile-Light and Dimmer, of which the following is a specification.

10 The object of my invention is to provide an automobile lamp of simple, durable and inexpensive construction.

15 More particularly it is my object to provide an automobile lamp of such type that the rays of light may be directed in different directions, and with different intensities, and different diffusions on the road in front of a car.

With these and other objects in view my invention consists in the construction, arrangement and combination of the various 20 parts of the device, whereby the objects contemplated are attained, as hereinafter more fully set forth, pointed out in my claims and illustrated in the accompanying drawings, in which:

25 Figure 1 shows a side elevation of a lamp embodying my invention, parts being broken away and parts being shown in cross section.

Fig. 2 shows a front elevation of the same; and

30 Fig. 3 shows a perspective view of the lamp, illustrating the manner in which it is mounted.

In the accompanying drawings I have used the reference numeral 10 to indicate 35 generally the casing of my improved lamp, which is tubular in form and is longitudinally elongated, as illustrated in Figs. 1 and 3.

The casing 10 is closed at its end 11 and 40 has at its other end a lens 12, the upper portion of which is made opaque at 13 in any desired way.

In the upper half of the casing 10 on the interior thereof is a channel-shaped reflector 14.

45 Mounted in the reflector 14 near the lens 21 is an electric lamp 15, and mounted in the rear part of the reflector 14 is another electric lamp 16.

50 The lamp casing 10 has on its opposite

sides laterally extending spindles 17 which are designed to be mounted in the arms of a bracket 18 which is supported on a frame 19.

The bracket 18 has at its rear end an outwardly extending portion 20 provided with an elongated slot 21.

On the lamp casing is a rearwardly extending pin 22 extended through the slot 21 and having nuts 23 and 24 on opposite sides 60 of said slot. By loosening the nut 23 the rear end of the lamp may be raised or lowered for directing the rays of light in different directions.

In the practical use of a lamp of this kind, 65 I have found that by using the two lights in the same lamp casing and elongating the lamp casing as here shown, there can be secured such a variety in the directing of the rays and the diffusion of them as to serve 70 the purpose of a dimmer and a proper light very satisfactorily, and also to secure the kind of light desired for a variety of circumstances.

It is obvious that the lamp may be tilted 75 as may be desired for still further increasing its range of use.

It will be noted that if the rear lamp 16 only is lighted, a long narrow light will be directed ahead of the machine, while if the 80 forward lamp 15 only is lighted there will be a comparatively wide sheet of light directed ahead of the machine and downwardly.

Some changes may be made in the construction and arrangement of the parts of my improved lamp without departing from the essential features and purposes of my invention, and it is my intention to cover by 85 my application any modified forms of structure or use of mechanical equivalents which may be reasonably included within the scope 90 of my claims.

I claim as my invention:

1. In a device of the class described, a 95 lamp having a casing substantially elongated, a reflector in the upper portion of said casing, a lens at one end of said casing, a light device in said casing adjacent to the reflector and adjacent to the lens, a second 100

2
lamp in said casing adjacent to the reflector and adjacent to the other end of the casing.

2. In a device of the class described, a lamp having a casing substantially elongated, a reflector in the upper portion of said casing, a lens at one end of said casing, a light device in said casing adjacent to the

reflector and adjacent to the lens, a second lamp in said casing adjacent to the reflector and adjacent to the other end of the casing, ¹⁰ and means for pivotally supporting said casing.

Des Moines, Iowa, July 11, 1918.
MARK COX.
